UNITED STATES PATENT OFFICE

PAUL HAHN, OF CASSEL-WILHELMSHOHE, GERMANY

METHOD OF MAKING OIL GAS

Application filed March 21, 1924, Serial No. 700,977, and in Germany February 12, 1924.

This invention relates to a method of producing synthetic oil gas from heavy oils. Numerous experiments have been made in this direction, and it has for instance been proposed to solve the problem by producing a mixture of heavy oil, steam and air, and then by partial combustion producing oil gas or by adding superheated steam to the oil.

10 In this manner the problem could however not be solved entirely as it was not known that, in order to obtain the highest possible caloric value, the condition has to be fulfilled, that the heavy oil must at first be in a gaseous state or that the vapor produced must be at least superheated before a gasifying medium, such as steam, hydrogen, oxygen, or ozone, is added.

The method of producing oil-gas, according to the invention, is based on this knowledge. The method consists in bringing the heavy oil to the purest possible gaseous state before a diluent medium, for instance steam, hydrogen, oxygen or the like, is added, eventually with the addition of air. If hydrogen and oxygen are used, the proportion between them should be practically or approximately the same as in steam or water. This mixture can for instance be gasified by partial combustion and utilized in any convenient manner. By the improved method the heavy oil could be decomposed or steam might be generated for any purpose. The vapors produced could for instance be recondensed in order to obtain from the same light hydrocarbons (benzine and the like), or the gases produced might be used for driving engines, the exhaust gases from said engine being utilized for vaporizing a liquid the boiling point of which is lower than that of the liquid fuel.

40 The gasifying of the liquid fuel which is atomized as finely as possible is carried through under pressure, e. g., by conducting the liquid fuel for instance successively through several spaces having narrow outlet ports (nozzles). When flowing through these nozzles the energy of flow is for the greatest part transformed into pressure so that the pressure is increased from nozzle

to nozzle. If desired small quantities of air are added to the liquid fuel to be gasified. The gasifying process may however be carried out in several phases. At the first phase the quantity of liquid fuel in a finely atomized state is for instance regulated and in the second phase the liquid fuel is exposed to the action of heat. In a third phase a decomposition of the liquid fuel is carried through by contact with the walls and by addition of the gasifying medium. In a fourth phase a molecular-kinetic action takes place in the nozzles in the form of a catalytic action either by the catalyst contacting with the oil vapor and gas, or by the surface of that substance, and at the fifth phase a chemical or physical transformation of the liquid fuel with a gasifying medium is effected.

I wish it to be understood that where I speak of gasifying the meaning is to produce carbon monoxide from carbon and oxygen and saturated hydrocarbons from unsaturated ones.

By molecular-kinetic action the following is understood:—The molecules strike on the inner surfaces of the nozzle walls as in these nozzles the velocity is transformed into pressure. The inlet opening of each nozzle is comparatively wide but the outlet opening is narrow and the counter pressure is increased by the gasifying medium which increases the surface of gas or steam by which also a catalytic effect is produced. Consequently the molecules press and strike on one another and on the inner surface of the nozzle wall when traversing the nozzle. The molecular action serves to loosen the structure of the oil.

The oil and the vapors and gases generated from the same are heated by the waste heat from the gas mixture which is burnt or from any other source of heat, so that the oil during its travel, up to the moment when it is mixed with the gasifying medium, is vaporized, dried and superheated. When steam is used as a gasifying medium the surprising phenomenon is perceived that the gasification is almost complete. Under certain conditions the steam is separated into hydrogen and oxygen, and eventually a chemical transformation of the steam or its constitu-

ents hydrogen and oxygen with the gaseous hydrocarbons takes place. At the outflow of this mixture, from the apparatus in which it has been produced the production of the constituents of the mixture, e. g. the production of the oil vapor and of the gasifying medium can be carried out in two separate vessels. These vessels might however be combined to form one apparatus. By the method according to the invention even heavy fractions of the oil can be thoroughly gasified, owing to the molecular-kinetic action in the nozzles, as this action prepares fractions which are difficult to volatilize for distillation by the hydrogen dissociated from the steam. Residues of the oil which cannot be gasified can be removed from the apparatus and used for other purposes, for instance for the production of briquettes.

An apparatus, adapted for carrying out the above described method, is shown in vertical section by way of example in the single figure of the accompanying drawing.

The liquid fuel, viz. crude oil is passed through valve a from a reservoir a' into a preliminary heater or vaporizer b . The heating means for the heater or vaporizer b are not shown. The top of this vaporizer is connected with the top of the reservoir a' by a pressure-equalizing pipe a^2 . The oil which has thus been vaporized flows through a tube c , the end of which extends upwardly into the preliminary vaporizer and which pre-heater or preliminary vaporizer b is moderately heated to the main shell of the gasifier d into which a vessel e is inserted which is composed of two parts having each a plurality of superposed and downwardly inclined sheet-metal plates f , f' , respectively. This main gasifier may be heated by any suitable source of heat. The partitions f , f' , the inner ends of which overlap one another and form practically narrow oblong or longitudinal nozzles α which extend over the entire width of the plates f and f' and through which the oil vapors and gases must flow in the direction of the arrows in order to get to the outlets g or m . The orifices of the nozzles formed by the partitions, are narrow and sharpedged wherfrom results, that the vapors and gases are strongly agitated and come in contact with the large heating plates or baffles f^1 , f^2 whereby a catalytic effect is attained. These plates or baffles consist of metal, and I have found that iron and nickel are particularly suited for the purpose in view. But the nozzles form, or act as, diffusers. The partitions which form the walls of the nozzles and which are heated in any convenient manner serve further to complete the gasification of the oil and to superheat the oil vapor, so that the oil comes out of the compartment e in the state of superheated oil vapor or at least in the state of vapor. The compartment is sup-

ported by means of projections f^3 upon brackets d^1 on the side wall of the outer casing d , and it is strongly pressed on said brackets by the lid d^2 of the outer casing or by the bottom of a reservoir for liquid fuel or the gasifying medium, mounted on the outer casing d . Water or steam flows from a reservoir h^1 at h into a preliminary heater or water evaporator i heated by any suitable source (not shown). The top of the reservoir h^1 is connected with the top of the vessel i by a pressure-equalizing tube h^2 . The water or steam injected into the heater flows in the direction of the arrows drawn in full lines through a tube k into a superheater l which may be of any convenient shape.

This superheater may be omitted.

The steam flows then into the intermediate space between the compartment e and the outer casing d and admixes with the oil vapor flowing in through apertures d^4 in the flange d^4 of lid d^2 which flange rests upon the compartment e , the mixture of steam and oil forms oil gas which flows out through the nozzle g . Near the outer nozzle air is sucked in twice at the inlets g^1 and g^2 . I think it proper to point at this place to the fact that catalysis during gasification is caused by the large heating surfaces of the catalytic plates f and f' assisted by the injection of steam. The oil is thus gasified by heating and reaction with hydrogen and oxygen dissociated from the steam which is assisted by the catalytic actions of the plates. At the top end of the gasifying vessel d a gas supply m is arranged designed for instance for autogenous welding.

The oil gas produced according to this method is adapted, besides other purposes, for heating rooms, boilers, ovens or furnaces for the metallurgic and ceramic industries, for the production of welding flames and the like, for internal combustion engines, steam engines and gas turbines as well as for illuminating purposes. The preliminary vaporizer b has in its bottom a discharge pipe b^1 through which the constituents of the oil which have not been vaporized may be withdrawn. In the lower part of tube c an opening c^1 is arranged through which the heavier fractions of the oil can flow from the vaporizer b into the tube c and then into gasifier d .

The pressure in the gasifier d affects the flow from reservoirs a^1 and h^1 . To avoid using separate pumps for feeding the oil or the water into these reservoirs the gas under pressure in the gasifier d (less small losses from friction) is connected through conduits h^2 and a^2 into these reservoirs so that the pressure in the same is approximately equal to the pressure in the gasifier d and an uniform admission of liquid to the apparatus is ensured by suitably adjusting the valves a and h .

The vaporization of the oil can also be effected by subjecting it partly or wholly to high pressure, and relieving it thereafter from this pressure, as pressure and heat, concerning their effect upon the oil in this process, are equivalents.

I wish it to be understood that I do not limit myself to all details described; departures in the details are possible which are no departures from the invention. Thus, for instance, matters, as regards the method and its effect, would not be changed if the direction of the fluids would be the reverse, that is to say, if the fluids would be introduced into the gasifying vessel at the top and withdrawn at the bottom thereof, or if the fluids would be conducted through said vessel in a horizontal direction. The catalytic action of the staggered plates would be absolutely the same. Their action and effect would also not be changed if they would have another shape than that shown in the drawing merely by way of example, it being, as a matter of course, presupposed that provision be made for the requisite intimate contact between the fluids and the said members.

By means of the described apparatus the gas is prepared as follows:

On its way the vapor of oil is subjected to violent thrusts by sudden alterations of the direction with a following contraction, a supply of heat and subsequent contraction, for instance in passing over from tube *c* into the gasifier *d*, in which are alternately arranged baffle-plates, with one another and being heated to 400° C. for instance.

This internal friction with continued supply of heat causes a molecular loosening of the structure of the different hydrocarbons, said structure offering little resistance in itself. Under this condition the mixture of oil vapors catalytically acts on the steam flowing towards at a temperature of 400 to 500° C. in the sense, that the loosening, otherwise at these temperatures only beginning, increases. Thus hydrogen becomes free and hydrogenates the hydrocarbons, which are non-saturated.

Said hydrocarbons form stable gases due to the heat.

The influence of the dissociated oxygen may probably be judged in such a manner, that by the oxidation of hydrocarbons, which decompose owing to their instability internal reactions arise, the final products of which are CO, H₂ and H₂O vapor. The resulting gas contains as constituents hydrocarbons of the methane series, H₂, CO, and small amounts of CO₂, O₂, and N₂. The liquid products are used similarly to gasoline.

I claim:—

1. A method of making oil gas; which comprises vaporizing oil in a heated vaporizing chamber, passing the oil vapors to a heated separate gasifying chamber, said

gasifying chamber having staggered and spaced catalytic metal plate baffles forming narrow spaces or nozzles; admitting steam to the lower portion of the gasifying chamber and mixing the oil vapors and the steam; passing the mixed oil vapors and steam in an upward direction through the nozzles and heated baffles, and thereby forming oil gas; and withdrawing the oil gas from the upper portion of the gasifying chamber. 70

2. A method of making oil gas; which comprises vaporizing oil in a heated vaporizing chamber, passing the oil vapors to a separate heated gasifying chamber having staggered and spaced catalytic metal plate baffles forming narrow longitudinal nozzles; admitting steam to the lower portion of said gasifying chamber, and mixing the oil vapors and the steam; passing the thus obtained mixture in an upward direction through said narrow longitudinal nozzles and said heated baffles so as to thereby form oil gas; and withdrawing the gas from the upper portion of the said gasifying chamber. 80

3. A method of making oil gas; which comprises vaporizing oil in a heated vaporizing chamber, passing the oil vapors to a separate heated gasifying chamber having staggered and spaced catalytic metal plate baffles forming narrow longitudinal nozzles; admitting oxygen and hydrogen in a gaseous state to the lower portion of said gasifying chamber, and mixing the oil vapors and the oxygen and hydrogen; passing the thus obtained mixture in an upward direction through said narrow longitudinal nozzles and said heated baffles so as to thereby form oil gas; and withdrawing the gas from the upper portion of the said gasifying chamber. 90

4. A method of making oil gas; which comprises vaporizing oil in a heated vaporizing chamber, passing the oil vapors to a separate heated gasifying chamber having staggered and spaced catalytic metal plate baffles forming narrow longitudinal nozzles; admitting steam to the lower portion of said gasifying chamber, and mixing the oil vapors and the steam; passing the thus obtained mixture through said narrow longitudinal nozzles and said heated baffles so as to thereby form oil gas; and withdrawing the gas from the said gasifying chamber. 100

In testimony whereof I affix my signature.

PAUL HAHN.
